UNITED STATES PATENT OFFICE.

HERBERT STORMS FITZGERALD, OF TARRYTOWN, NEW YORK.

HOOK AND EYE.

1,254,491.

Specification of Letters Patent. Patented Jan. 22, 1918.

Application filed October 3, 1917. Serial No. 194,486.

To all whom it may concern:

Be it known that I, HERBERT STORMS FITZGERALD, a citizen of the United States, residing at Tarrytown, in the county of Westchester, State of New York, have invented a new and useful Hook and Eye; and I do hereby declare the following to be a full, clear, and exact description of the invention, such as will enable others skilled in the art 10 to which it appertains to make and use the same.

The present invention relates to certain new and useful improvements in hook and eye fasteners, and has for its object to provide 15 a hook which embodies novel features of construction whereby the edge portion of the garment or other member to which it is secured will be prevented from turning back and gaping in an objectionable manner.

20 Further objects of the invention are to provide a fastener of this character which is comparatively simple and inexpensive in its construction, which can be formed from a single length of wire, which can be readily 25 stitched or otherwise secured to a garment or like member, and which is not liable to become accidentally released or unfastened when in use.

With these and other objects in view, the 30 invention consists in certain novel combinations and arrangements of the parts as will more fully appear as the description proceeds, the novel features thereof being pointed out in the appended claims.

35 For a full understanding of the invention, reference is to be had to the following description and accompanying drawing, in which:—

Figure 1 is a top plan view of a hook constructed in accordance with the invention.

Fig. 2 is a side elevation of the same.

Fig. 3 is a bottom plan view of the hook member.

Fig. 4 is a plan view of a conventional 45 form of eye which may be used in connection with the hook member.

Corresponding and like parts are referred to in the following description and indicated in all the views of the drawings by the 50 same reference characters.

Referring to the drawings, which illustrate one embodiment of the invention, the reference character A designates a flat elongated base, and B a hook member which 55 springs from an intermediate portion of the

base and extends over the base in coöperative relation thereto, said hook member being adapted to engage a conventional eye C, such as that illustrated by Fig. 4. The hook fastener is preferably formed from a single 60 length of wire, the base A being shown as including a middle strand 1, and side strands 2 and 3. These several strands of wire have a parallel relation to each other, and the middle strand 1 extends substantially the 65 full length of the base, while the side strands 2 and 3 extend from an intermediate point in the base to opposite ends thereof. The hook member B springs from this intermediate point in the base and includes 70 spaced sides which are formed by returning the side strand 2 and deflecting the opposite side strand 3 upwardly. The nose of the hook member is deflected downwardly toward the base, as indicated at 4, the end of 75 the hook member being looped at 5. The strands 1 and 3 of the base extend away from the mouth of the hook member and terminate in an integral eye 6, while the strands 1 and 2 extend in the opposite direction 80 and have the free ends thereof curved outwardly in the plane of the base to provide the usual eye 7. The portion of the middle strand 1 under the overhanging portion of the hook may be crimped upwardly at 8 to provide a hump for preventing 85 accidental disengagement of the eye C from the hook when the fastener is in use.

The hook fastener may be secured to the outer overlapping edge of the crimp or like member by means of suitable stitching engaging the eyes 6 and 7, and the eye 6 which extends away from the base of the hook member will be positioned at the free outer edge of the garment, thereby preventing 90 this outer edge from turning outwardly or gaping in an objectionable manner. The coöperating eye C shown by Fig. 4, will be secured to the underlying edge of the garment which is to be detachably fastened to 95 the outer edge of the garment, and can be forcibly engaged or disengaged from the hook member B in the usual manner. It will be understood, however, that the improvement resides in the eye 6 which is provided upon a forward extension of the base for engaging the free outer edge of the garment to prevent it from turning outwardly when the two edges of the garment are secured together by the fastening means. 100 105 110

Having thus described the invention, what I claim as new and desire to secure by Letters Patent, is:—

1. A hook fastener including a base formed of a middle strand and two side strands of wire, the middle strand extending substantially the full length of the base while the side strands extend in opposite directions from an intermediate portion of the base to opposite ends thereof, and a hook member springing from said intermediate portion of the base and formed by returning one side strand and deflecting the other side strand upwardly, the middle strand and one side strand terminating at one end of the base in a fastening eye, while the middle strand and other side strand terminate at the other end of the base in fastening eyes.
2. A hook fastener including a base formed of a middle strand and two side strands of wire, the middle strand extending substantially the full length of the base while the side strands extend in opposite directions from an intermediate portion of

the base to opposite ends thereof, and a hook member springing from said intermediate portion of the base and formed by returning one of the side strands and deflecting the other side strand upwardly, the middle strand and one side strand extending in a direction remote from the mouth of the hook member and terminating in a fastening eye, while the middle strand and other side strand extend under the open end of the hook member and are returned laterally in opposite directions to provide fastening eyes, all of the said fastening eyes being in the plane of the base, and an intermediate portion of the middle strand being crimped upwardly into the throat of the hook member.

In testimony whereof I have signed my name to this specification in the presence of two subscribing witnesses.

HERBERT STORMS FITZGERALD.
